corporation of Ohio

Original application February 6, 1941, Serial No.
377,715. Divided and this application October
16, 1941, Serial No. 415,237

4 Claims. (Cl. 197—133)

This invention relates to an apparatus for feeding a plurality of paper webs through a machine which produces multiple copies of a form, the invention more particularly relates to a feeding mechanism for such a machine.

An object of the invention is to provide a feeding mechanism for feeding paper through a machine which has a circular platen associated therewith over which the paper web passes.

Another object of the invention is to provide a feeding mechanism for feeding a paper web over a circular platen by engaging the web along the edges thereof.

Another object of the invention is to provide a feeding mechanism consisting of a wheel having a plurality of needles therein which are adapted to engage the edge of a paper web or sheet which is to be fed over a circular platen.

Another object of the invention is to provide a needle wheel feeding mechanism upon a typing machine which is rotated concomitantly with the platen thereof for feeding a paper sheet or web over the platen.

It is another object of the invention to provide a needle feeding mechanism associated with a circular platen in such a manner that the feeding mechanism may be engaged with a paper web or sheet to be fed over the platen or can be disengaged from the web or sheet to permit movement of the sheet with respect to the platen, or movement between adjacent sheets.

It is another object of the invention to provide a needle feeding mechanism for advancing paper over a platen.

It is still another object of the invention to provide a needle feeding mechanism associated with a typewriter platen for feeding paper webs over said platen.

It is still another object of the invention to provide a needle feeding mechanism for a paper handling machine wherein the needles are retractible.

It is another object of the invention to provide a needle feeding mechanism associated with a rotatable platen for feeding paper over said platen when the same is rotated.

Further objects and advantages will become apparent from the following description and from the drawing.

This application is a division of my copending application Serial No. 377,715, filed February 6, 1941 (now Patent No. 2,305,988, granted Dec. 22, 1942).

In the drawing:

Figure 1 is a perspective view of a typewriter

platen showing a needle feeding mechanism associated therewith.

Figure 2 is a plan view of a typewriter platen having a needle feeding mechanism associated therewith in a modified manner from the showing of Figure 1.

Figure 3 is a cross-sectional view taken along line 3—3 of Figure 2.

Figure 4 is a plan view of a typewriter platen showing the needle feeding mechanism carried within the platen.

Figure 5 is an end view, partially in cross section of the mechanism shown in Figure 4 and taken along the line 5—5 thereof.

Figure 6 is a cross-sectional view taken along line 6—6 of Figure 5.

Figure 7 is a cross-sectional view of a portion of the typewriter platen taken along line 7—7 of Figure 5.

20 This invention relates to a feeding mechanism for feeding paper over a circular platen, and is disclosed in the drawing and described in the specification as being associated with the platen of a typing machine. The conventional manner of feeding paper through a typing machine is to apply pressure upon the surface of the paper sheet or web to force the same into engagement with the circular platen of the typing machine so that the paper is fed by frictional engagement with the platen when the same is rotated. In this invention the feeding mechanism consists of a plurality of needles which are suitably mounted and rotated concomitantly with the platen of the typing machine and are so positioned

35 with respect to the platen that the needles engage the edges of the paper to be fed through the machine so that they pierce the paper to make positive engagement therewith and thus draw the paper web over the platen. The needles are driven concomitantly with rotation of the platen of the typing machine so that rotation of the needles will draw the paper through the machine at the same rate it is fed over the periphery of the platen.

40 45 The feeding mechanism of this invention has particular merit when used in combination with a cylindrical platen such as that found on a typewriter since it overcomes the difficulty of slippage between adjacent paper sheets as fed through the machine by frictional engagement. Furthermore, the feeding mechanism of this invention has particular merit when feeding a "fan-fold" type of pre-folded and pre-printed form. Such forms are well known in the art and are of the type which are folded both transverse-

ly and longitudinally to provide a plurality of copies of a form which are retained together by their edges.

When feeding such forms over a cylindrical platen the longitudinally folded edges thereof wrinkle badly. This is true in the conventional types of typewriter wherein the feed of the fan-fold form is produced by frictional engagement of the form with the typewriter platen. While the use of the fan-fold form will be described with more particularity with regard to its use in a typewriter, yet it is to be understood that such a description does not preclude the use of other forms.

The feeding mechanism of this invention is shown as used in cooperation with a cylindrical platen, the platen being usable upon any printing or typing machine. The mechanisms of Figures 1 to 7 inclusive are somewhat diagrammatic, but the essential features for establishing cooperating working relation between the mechanisms of the machine and the applicant's needle wheel feeding mechanism are sufficiently shown to obtain a clear understanding of the operation thereof.

In Figure 1 a cylindrical platen 135 is carried upon a shaft 136 by which the platen is suitably mounted within a printing or typing machine. The platen 135 is a conventional type usually associated with such machines. The shaft 136 carries a spur gear 137 and a hand wheel 138 by which the platen 135 can be manually rotated. The hand wheel 138 is the conventional wheel provided on a platen shaft. A spur gear 139 is in operative association with the spur gear 137 and is suitably carried upon a shaft 140 mounted in the typewriter frame which also carries the shaft 136 to thereby establish working relation between the spur gears 137 and 139. A shaft 141 is arranged in parallel relation with respect to the shaft 136 and is carried by the typewriter frame in any suitable manner. A spur gear 142, which is in operative working relation with the gear 139, is mounted upon the shaft 141.

The mechanism for drawing a paper sheet or web over the platen 135 consists of the needle wheels 143 having needles 144 mounted radially about the periphery of the wheels 143. The wheels 143 are suitably secured upon the shaft 141 and are positioned thereon in spaced relationship to permit the needles 144 to pierce opposite parallel edges of a paper web 145. The needle wheels 143 are retained in spaced relationship upon the shaft 141 by means of the end collars 125 and the central spacing collar 126. Collars 126 of different widths can be provided to space the wheels 143 in proper relation for different widths of paper.

As disclosed in Figure 1 the needle wheels 143 are positioned rearwardly of the platen 135 so that a paper web 145 can be fed into the typing machine and placed under the platen 135 in the conventional manner. When a paper web or sheet is placed within the typing machine it may be fed over the platen manually and placed in its proper longitudinal position. The web or sheet 145 is then positioned horizontally over the needle wheels 143 so that the needles 144 can pierce the edges of the sheet 145 for drawing the same through the typing machine. In order to maintain the web or sheet 145 in engagement with the needles 144 and thus insure feeding of the paper through the typing machine, a weighted roller 146 is positioned about the needle wheels 143. The roller 146 is carried upon a shaft 147 which

is supported upon the frame of a typing machine. The shaft 147 is preferably movable vertically with respect to the needle wheels 143 so that the paper web 145 can be placed upon the needles 144. The roller 146 is provided with an annular recessed ring 146a which aligns with the needles 144 so that they will not engage the surface of the roller 146.

The gears 137, 139 and 142 are so selected that the needle wheels 143 will be rotated at a peripheral speed which is equal to the peripheral speed of the platen 135 so that the paper web 145 will be moved through the typing machine without occasioning slippage between the web 145 and the platen 135. When the platen 135 is rotated by the mechanism of the typing machine or by the hand wheel 138 the needle wheels 143 will be rotated through the interconnecting gear wheels so that whenever the platen 135 is moved either for line spacing by the mechanism of the typing machine or for removing the sheet 145 from the machine that the needle wheels 143 insure positive movement of the paper over the platen 135.

In Figures 2 and 3 there is shown a slightly modified arrangement of the needle feeding mechanism in cooperation with a cylindrical platen. In this arrangement the platen 135a is provided with an undercut portion which forms an annular ring 148. The platen shaft 136a carries a spur gear 131a in the same manner as described in Figure 1.

In this modification, however, the needle wheel feeding mechanism is positioned in front of the platen 135a and is adapted to engage the paper web 145a from the top surface thereof. The needle wheel 143a is carried upon a shaft 149 upon which there is secured a spur gear 137 so that whenever the platen 135a is rotated the needle wheel 143a will be rotated concomitantly therewith for retaining the paper web 145a in surface engagement with the platen 135a and for feeding the same through the typing machine. The needle wheel 143 carries needles 160 which are aligned with the annular ring 148 so that they can pierce the paper web 145a to drivingly engage the same when rotated. The shaft 149 is preferably movable with respect to the platen 135a so that it can be lifted from its adjacent position with respect to the platen 135a to permit shifting of the paper web 145a for aligning the same with respect to the type bars of the typing machine.

It can be seen in both of the arrangements previously described that the paper web 145 passing over the cylindrical platen 135 will not have friction applied to any portion of its surface to retain the same in pressure engagement with the platen 135 for driving the paper through the typing machine. Thus, when the web forms, which are longitudinally folded, are fed over the cylindrical platen 135, the longitudinal fold lines thereof will not wrinkle. Also, it can be seen that a more even feeding of the paper web will be obtained due to the non-wrinkling of the longitudinal fold lines and that the line register of adjacent sheets will be more uniform. The disadvantage of angular displacement of the adjacent form faces is eliminated.

In Figures 4 to 7 inclusive there is shown a modified form of needle feeding apparatus wherein the needle feeding mechanism is mounted within a cylindrical platen, and wherein the needles are retractable in a manner to release the paper web after it has been properly fed over the platen.

In this arrangement, a cylindrical platen 155 is carried upon a shaft 156. A plurality of retractible needle assemblies 157 is positioned radially about the perimeter of the platen 155.

These retractible needle assemblies consist of a cup member 158 carried within the platen 155. A second cup member 159 is slidably associated with the cup member 158 for reciprocation therein. The cup member 159 carries a needle 160 which is adapted to protrude through an opening 161 provided in the cup 151. A compression spring 162, which is secured at its opposite ends to the cups 158 and 159 respectively, is arranged to normally position the cups in their extended position to thereby cause retraction of the needle 160 within the cup 158.

In order to extend the needles 160 from the cups 158 a cam 163 is positioned upon the shaft 156. This cam 163 has a slot 164 which will permit vertical movement of the cam with respect to the interior surface 165 of the platen 155, the interior surface 165 being provided by a recess in the end of the platen 155 and in which the retractible needle assemblies 157 and the cam 163 are located.

The cam 163 is rigidly secured to an arm 166. The arm 166 is pivotally carried upon an arm 167 at 168, the arm 167 being pivotally mounted at 169 upon a stationary part of the printing or typing machine. It will thus be seen that the cam 163 is prevented from rotation by the arms 166 and 167, yet will be permitted vertical movement with respect to the interior surface 165 of the platen 155.

The normal position of the cam 163 with respect to the surface 165 of the platen 155 is as shown in Figure 5, whereby the needles 160 will be driven outwardly when the cup 159 engages the surface of the cam 163. When the needle assembly 157 passes across the surface of the cam 163 the spring 162 will cause automatic retraction of the needle 160 into the cup 158. It may thus be seen that a paper web 170 which is to be fed through a printing or typing machine will be engaged by the needles 160 throughout a portion of the rotation of the platen 155, the needles 160 forcibly moving the web 170 with the platen 155. When the needles are in the position of the needle assembly 157a, see Figure 5, the needles will have been retracted from the web 170 to release the same and permit the web to be removed or shifted while in the machine.

There will be times when it is desirable to shift the web 170 with respect to the platen 155 while the web is within the machine and in engagement with the platen, or to shift adjacent paper webs which are fed over the platen simultaneously. To permit such shifting the slot 164 in the cam 163 permits the cam to be moved vertically whereby the needle cups 159 normally engaged thereby when positioned adjacent thereto will be released to permit the springs 162 to retract the needles 160. A spring 171 is secured upon the cam 163 by means of the screws 172. The spring 171 is so shaped that it will retain the cam 163 in position, as shown in Figure 5, or in a raised position wherein the cam 163 will be raised vertically with respect to the shaft 156 to permit release of the needle assemblies engaged thereby.

The apparatus described is particularly adaptable for feeding a fan-fold form over a cylindrical platen, but it will be readily understood that the feeding mechanism is just as applicable to the

feeding of individual sheets, or individual adjacent sheets forming a multiple copy form.

It will be understood by those versed in the art that the mechanism of this invention is applicable to any machine wherein multiple copies of a form is to be reproduced, and wherein there is the necessity for retaining alignment or registration of adjacent form faces.

It is therefore within the purview of this application to include those mechanisms which require mechanical changes but which fall within the scope of the invention.

Having thus fully described my invention, what I claim as new and desire to secure by Letters Patent is:

1. An apparatus specially adapted for feeding a plurality of superposed paper sheets through a typewriter over the platen thereof and maintaining them continuously in determined superposed alignment over the entire surface area of the sheets to simultaneously position superposed type lines on the sheets at the typing level of the machine including, a rotatable platen over which a plurality of superposed paper sheets are moved in such a manner that they encompass a substantial portion of the circumference of the platen of the typewriter when moving thereover through the typewriter, and feeding wheels having a plurality of needles extending radially therefrom positioned above the platen of the typewriter and to the rear of the superposed sheets as they pass over the platen to cause the needles to pierce the paper sheets after they have passed through the machine and beyond the typing level thereof and provide the sole means for feeding the paper sheets over the platen at the peripheral speed of rotation of the platen, said needles being spaced radially in said wheels in a manner that at least one needle is always extending through the paper sheets passing over the platen to prevent any shifting of the sheets with respect to one another to maintain superposed type lines on the sheets continuously in superposed alignment whereby to simultaneously position them at the typing level and cause the radially outermost sheet passing over the platen to feed at a greater surface speed than the radially innermost sheet to thereby continuously maintain juxtaposed alignment between adjacent sheets.

2. An apparatus specially adapted for feeding a plurality of superposed paper sheets through a typewriter over the platen thereof and maintaining them continuously in determined superposed alignment over the entire surface area of the sheets to simultaneously position superposed type lines on the sheets at the typing level of the machine, a rotatable platen over which a plurality of superposed paper sheets are moved in such a manner that they encompass a substantial portion of the circumference of the platen of the typewriter when moving thereover through the typewriter, and feeding wheels having a plurality of needles extending radially therefrom positioned above the platen of the typewriter and to the rear of the superposed sheets as they pass over the platen to cause the needles to pierce the paper sheets after they have passed through the machine and beyond the typing level thereof and provide the sole means for feeding the paper sheets over the platen at the peripheral speed of rotation of the platen, said feeding wheels being disposed relative to said platen wherein they are positioned a substantial distance inwardly from the ends thereof to engage paper substan-

tially narrower than said platen and any size thereover up to the full length of said platen, said needles being spaced radially in said wheels in a manner that at least one needle is always extending through the paper sheets passing over the platen to prevent any shifting of the sheets with respect to one another to maintain superposed type lines on the sheets continuously in superposed alignment whereby to simultaneously position them at the typing level and cause the radially innermost sheet to continuously maintain juxtaposed alignment with radially adjacent sheets.

3. An apparatus specially adapted for feeding a plurality of superposed paper sheets through a typewriter over the platen thereof and maintaining them continuously in determined superposed alignment over the entire surface area of the sheets to simultaneously position superposed type lines on the sheets at the typing level of the machine, a rotatable platen over which a plurality of superposed paper sheets are moved in such a manner that they encompass a substantial portion of the circumference of the platen of the typewriter when moving thereover through the typewriter, feeding wheels having a plurality of needles extending radially therefrom positioned above the platen of the typewriter and to the rear of the superposed sheets as they pass over the platen to cause the needles to pierce the paper sheets after they have passed through the machine and beyond the typing level thereof and provide the sole means for feeding the paper sheets over the platen at the peripheral speed of rotation of the platen, said feeding wheels being disposed relative to said platen wherein they are positioned a substantial distance inwardly from the ends thereof to engage paper substantially narrower than said platen and any size thereover up to the full length of said platen, said needles being spaced radially in said wheels in a manner that at least one needle is always extending through the paper sheets passing over the platen to prevent any shifting of the sheets with respect to one another to maintain superposed type lines on the sheets continuously in superposed alignment whereby to simultaneously position them at the typing level and cause the radially innermost sheet to continuously maintain juxtaposed alignment with radially adjacent sheets, shaft means parallel to said platen for supporting said wheels a substantial distance inwardly from the ends of said platen and to which the wheels are secured, drive means connecting said shaft to said platen to rotate said wheels at the periph-

5 4. An apparatus specially adapted for feeding a plurality of superposed paper sheets through a typewriter over the platen thereof and maintaining them continuously in determined superposed alignment over the entire surface area of the sheets to simultaneously position superposed type lines on the sheets at the typing level of the machine, a rotatable platen over which a plurality of superposed paper sheets are moved in such a manner that they encompass a substantial portion of the circumference of the platen of the typewriter when moving thereover through the typewriter, feeding wheels having a plurality of needles extending radially therefrom positioned above the platen of the typewriter and to

10 15 20 25 30 35 40 45 50 the rear of the superposed sheets as they pass over the platen to cause the needles to pierce the paper sheets after they have passed through the machine and beyond the typing level thereof and provide the sole means for feeding the paper sheets over the platen at the peripheral speed of rotation of the platen, said feeding wheels being disposed relative to said platen wherein they are positioned a substantial distance inwardly from the ends thereof to engage paper substantially narrower than said platen and any size thereover up to the full length of said platen, said needles being spaced radially in said wheels in a manner that at least one needle is always extending through the paper sheets passing over the platen to prevent any shifting of the sheets with respect to one another to maintain superposed type lines on the sheets continuously in superposed alignment whereby to simultaneously position them at the typing level and cause the radially innermost sheet to continuously maintain juxtaposed alignment with radially adjacent sheets, shaft means parallel to said platen for supporting said wheels a substantial distance inwardly from the ends of said platen and to which the wheels are secured, drive means connecting said shaft to said platen to rotate said wheels at the peripheral speed of the platen, and pressure roll means engaging said wheel means to apply pressure on the paper sheets passing thereover to force the needles to pierce the sheets, said pressure roll means comprising a roller having a groove therein positioned adjacent said shaft so that the needles enter said groove.

WILLIAM C. PFEIFFER.
